UNITED STATES PATENT OFFICE.

DAVID M. PALMER, OF LOS ANGELES, CALIFORNIA.

ELECTRIC OSCILLATOR.

1,097,873.

Specification of Letters Patent. Patented May 26, 1914.

Application filed June 24, 1913. Serial No. 775,554.

To all whom it may concern:

Be it known that I, DAVID M. PALMER, a citizen of the United States, residing at Los Angeles, in the county of Los Angeles and State of California, have invented a new and useful Electric Oscillator, of which the following is a specification.

This invention relates to an electric oscillator especially designed for operating a semaphore signal, and the main objects of the invention are to provide an electric oscillator in which the oscillations are produced by magnets, and the circuits through the magnets are controlled by mechanism of simple and economical construction and of great durability.

Referring to the drawings: Figure 1 is a front elevation of the device as embodied in a complete signal. Fig. 2 is a section on line x^2-x^2 , Fig. 3. Fig. 3 is a plan view. Fig. 4 is a section on line x^4-x^4 , Fig. 3. Fig. 5 is a section on line x^6-x^6 , Fig. 3. Fig. 6 is a diagram of the wiring. Fig. 7 is an enlarged side elevation with the cover removed, part of the device being in section. Fig. 8 is an enlarged view, similar to Fig. 5, showing one position of the parts. Fig. 9 is a view similar to Fig. 8, showing another position of the parts. Fig. 10 is a view similar to Fig. 8, showing another position of the parts.

The oscillator comprises two pairs of magnets 1 and 2, mounted on a base 3. The magnets 1 are adapted to attract an armature 4 and the magnets 2 are adapted to attract an armature 5, the armatures 4 and 5 being carried on a walking beam 6 which is secured to the upper end of a post 7 rigidly secured to a shaft 8, shaft 8 being journaled in bearings 9. Springs 10 are arranged in the ends of cores 11 of the magnets to act as buffers to prevent shock to the mechanism at the extreme positions of stroke of the armature.

The circuit through each pair of magnets is controlled by a switch consisting of a relatively stationary contact 12 and a movable contact 13. The contact 12 comprises a plunger which is mounted in a socket 14 and is yieldingly supported by a compression spring 15. The movable contact 13 comprises a plunger mounted within a socket 16 and yieldingly supported by a compression spring 17 and having a stem 18 which projects up from the socket 16 and enables the plunger to be depressed by a rock arm 19

which is pivoted on a stationary pin 20 mounted in a plate 21 which projects up from the base 1, see Fig. 7. The rock arm 19 has two inclined faces 22 and 23 which diverge from a central projection 24 and a ball 25 is yieldingly held against one or the other of the faces 22 and 23 by means of a compression spring 26 which is arranged in a socket 27.

Rigidly secured to the shaft 8 is an arm 28 carrying a cross bar 29 in the ends of which are adjusting screws 30. The rock arm 19 is moved into either of its positions by movements of cross bar 29 transmitted through screws 30 to the rock arm 19 and there is a sufficient lost motion between the screws 30 and rock arm 19 to allow the rock arm 19 to remain in either of its positions until the cross bar 29 has nearly reached the end of its stroke, at which time one of the screws 30 contacts with rock arm 19 and moves it down, swinging the projection 24 across the ball 25 and the end of the rock arm 19 which is depressed, operates to depress the corresponding switch plunger 13 and bring it into connection with the lower plunger 12, thus closing the circuit through the pair of magnets which are in circuit therewith. The pair of magnets which are thus energized attract their armature and swing the cross bar 29 in a corresponding direction, thereby rocking the shaft 8 reversely. This movement continues until the screw 30 strikes the rock arm 19 and tilts the latter into its opposite position, thereby depressing the other switch plunger 13 and closing the circuit through the other set of magnets, whereupon the shaft 8 is tilted in a reverse direction by a reverse operation of the parts as previously described. This results in imparting an oscillatory movement to the shaft 8. This movement may be utilized in various ways, for example, a semaphore 31 may be mounted on an arm 32 which is secured to the shaft 8 and a counterbalancing weight 33 may be secured to the lower end of shaft 8 by a spring 34 which acts to prevent too sharp a shock at the extreme of movement which would occur if the weight 33 were rigidly secured to arm 32 on account of the momentum of the weight 33. Also an electric light 35 may be carried by an arm 36 projecting from the shaft 8 which will oscillate with the semaphore and be visible at night.

The operating parts of the device may be

inclosed in a case 36', as shown in Fig. 1, and supported by a pedestal 37. A gong 38 may also be employed and caused to ring whenever the device is in operation, but 5 these features form no part of the invention. The device may be electrically connected as indicated in Fig. 6, the shovable plungers 13 being connected by wires 39 and 40 with one side of the main circuit 41 which may comprise 10 a part of the railroad track or extend therealong and be closed in any desired manner by a car when the car is at a definite point. The stationary terminals 12 may be connected by wires 42 and 43 with magnets 1 and 2 respectively and magnets 1 and 2 connected by wires 44 and 45 with the other side of the main circuit 46.

What I claim is:

1. Oppositely arranged magnets, an oscillating armature adapted to be attracted by said magnets, a switch in connection with one magnet, a switch in connection with the other magnet, a main circuit with which each of said switches is connected, a rock 20 arm pivoted independently of said oscillating armature, and adapted to alternately close said switches, and means associated with said armature for pivotally rocking said rock arm by the movement of the armature allowing an independent movement of the armature for a large part of its stroke without tilting the rock arm.

2. Oppositely arranged magnets, a pair of oscillating armatures adapted to be respectively attracted by said magnets, a switch in connection with one magnet, a switch in connection with the other magnet, a main circuit with which each of said switches is connected, a rock arm pivoted independently 30 of said oscillating armatures and adapted to alternately close said switches, means associated with said armatures for moving against said rock arm to positively rock the same, allowing an independent movement 40 of the armatures for a large part of their stroke without tilting the rock arm, and an oscillatory shaft supporting said armatures, said rock arm being pivoted at a point above said shaft.

50 3. Oppositely arranged magnets, a pair of oscillating armatures adapted to be respectively attracted by said magnets, a switch in connection with one magnet, a switch in connection with the other magnet, a main 55 circuit with which each of said switches is connected, a rock arm pivoted independently of said oscillating armatures and adapted to alternately close said switches, means associated with said armatures for moving 60 against alternate opposite ends of said rock arm for positively rocking the same, allowing an independent movement of the armatures for a large part of their stroke without tilting the rock arm, an oscillatory shaft 65 supporting said armatures, said rock arm

being pivoted at a point above said shaft, and means for yieldingly holding said rock arm in either of its positions.

4. Oppositely arranged magnets, a pair of oscillating armatures adapted to be respectively attracted by said magnets, a switch in connection with one magnet, a switch in connection with the other magnet, a main circuit with which each of said switches is connected, a rock arm pivoted independently 70 of said oscillating armatures and adapted to alternately close said switches, means associated with said armatures for moving against said rock arm to positively rock the same, allowing an independent movement of the armatures for a large part of their stroke without tilting the rock arm, an oscillatory shaft supporting said armatures, 75 said rock arm being pivoted at a point above said shaft, said rock arm having a projection on its lower side with diverging faces, and a ball yieldingly held against one or the other of said faces.

5. Oppositely arranged magnets, a pair of oscillating armatures adapted to be respectively attracted by said magnets, a switch in connection with one magnet, a switch in connection with the other magnet, a main circuit with which each of said oscillating armatures is connected, a rock arm pivoted independently 80 of said oscillating armatures and adapted to alternately close said switches, means associated with said armatures for rocking said rock arm, allowing an independent movement of the armatures for a large part of their stroke without tilting the rock arm, an oscillatory shaft supporting said armatures, 85 said rock arm being pivoted at a point above said shaft, an arm rigidly mounted on said shaft, a cross bar on said arm, and adjusting screws in the ends of said cross arm adapted to strike against the rock arm to actuate the latter and positively move the rock arm to control said switches.

6. Oppositely arranged magnets, a pair of oscillating armatures adapted to be respectively attracted by said magnets, a switch in connection with one magnet, a switch in connection with the other magnet, a main 90 circuit with which each of said switches is connected, a rock arm pivoted independently of said oscillating armatures and adapted to alternately close said switches, means associated with said armatures for rocking said rock arm, allowing an independent movement of the armatures for a large part of their stroke without tilting the rock arm, an oscillatory shaft supporting said armatures, 95 said rock arm being pivoted at a point above said shaft, an arm rigidly mounted on said shaft, a cross bar on said arm, and adjusting screws in the ends of said cross arm adapted to strike against the rock arm to actuate the latter and positively move the rock arm to control said switches.

7. Oppositely arranged magnets, a pair of oscillating armatures adapted to be respectively attracted by said magnets, a switch in connection with one magnet, a switch in 100

connection with the other magnet, a main circuit with which each of said switches is connected, a rock arm pivoted independently of said oscillating armatures and adapted to alternately close said switches, means associated with said armatures for rocking said rock arm, allowing an independent movement of the armatures for a large part of their stroke without tilting the rock arm, 10 an oscillatory shaft supporting said armatures, said rock arm being pivoted at a point above said shaft, an arm rigidly secured to said shaft, a pendulous spring extending from one end of said arm, and a pendulum weight on the lower end of said spring.

8. Oppositely arranged magnets, a pair of oscillating armatures adapted to be respectively attracted by said magnets, a switch in connection with one magnet, a switch in 20 connection with the other magnet, a main circuit with which each of said switches is

connected, a rock arm pivoted independently of said oscillating armatures and adapted to alternately close said switches, means associated with said armatures for rocking 25 said rock arm, allowing an independent movement of the armatures for a large part of their stroke without tilting the rock arm, each of said switches comprising a relatively stationary plunger and a movable 30 plunger, a spring yieldingly supporting the relatively stationary plunger, and a spring yieldingly supporting the movable plunger to cushion the impact of the rock arm against the ends of the plungers.

In testimony whereof, I have hereunto set my hand at Los Angeles, California, this 17th day of June, 1913.

DAVID M. PALMER.
